UNITED STATES PATENT OFFICE.

BENJAMIN A. LEGG, OF COLUMBUS, OHIO, ASSIGNOR TO THE LECHNER MANUFACTURING COMPANY, OF SAME PLACE.

CHAIN FOR CONVEYERS.

SPECIFICATION forming part of Letters Patent No. 378,139, dated February 21, 1888.

Application filed December 18, 1886. Serial No. 221,934. (No model.)

To all whom it may concern:

Be it known that I, BENJAMIN A. LEGG, a citizen of the United States, residing at Columbus, in the county of Franklin and State of Ohio, have invented certain new and useful Improvements in Chains for Conveyers, of which the following is a specification, reference being had therein to the accompanying drawings.

10 Figure 1 is a side elevation of my invention. Fig. 2 is a top or plan view. Fig. 3 is a vertical section on line $x-x$, Fig. 1. Fig. 4 is a horizontal section on line $y-y$, Fig. 1.

The object of this invention is to construct 15 an endless carrier which shall run with but little friction, and consequently require but little power and involve a comparatively small wear of any of the parts.

Like letters indicate like parts in all of the 20 figures.

Prior to the date of my invention it was customary to construct horse-powers and similar machines with metal links arranged in pairs at opposite ends of the "lags" upon which the horse walks, these links being tied to each other by rods a little longer than the width of the 25 endless platform, and having anti-friction wheels mounted upon the ends of those rods outside of the ends of the lags to run upon supporting ways or tracks. In machines of this sort it was customary to construct the links with lugs or downward extensions at each end to receive these rods, in order that the rods might take into notches of the wheels traversed by the endless platform; but in such machines it would have been impossible to mount the anti-friction wheels above referred to between the links and underneath the lugs. Again, in Patent No. 340,321, to Jeffrey, there 30 is shown a chain having anti-friction rollers surrounding the pintles and traversing a supporting-track; but in that chain the pintles are in line with the side bars of the chain, so that the anti-friction-rollers project equally above and below the edges of the side bars, whereby it is necessary to interpose a series of upwardly-projecting ears or wings between the conveyer-bottoms and the side bars.

My invention relates to side bars provided 35 at their ends with downwardly-projecting lugs

having pintle-seats, whereby the upper edges of the chain-links may be formed on straight lines, and thereby adapted to receive and support the conveyer-sections throughout practically their entire length.

A B C D indicate, respectively, the bars, the legs, and the inwardly-projecting sleeves of which the links are formed. Of these parts the leg A projects downward from the end of the side bar, B, and is provided with a pintle-seat, a. 55 These pintle-seats are by preference slightly longer in one diameter than the other, for a purpose which will be explained. Each leg C is provided at its lower end with an inwardly-projecting sleeve, D, having a pintle-seat, d, 60 which is circular in cross-section and of substantially uniform diameter throughout.

A B C D indicate, respectively, the bars, the legs, and the inwardly-projecting sleeves of which the links are formed. Of these parts the leg A projects downward from the end of the side bar, B, and is provided with a pintle-seat, a. 55 These pintle-seats are by preference slightly longer in one diameter than the other, for a purpose which will be explained. Each leg C is provided at its lower end with an inwardly-projecting sleeve, D, having a pintle-seat, d, 60 which is circular in cross-section and of substantially uniform diameter throughout.

By an examination of Fig. 2 it will be seen

that the legs A A are not in plane with the bars B B, but are connected therewith by brackets or offsets b b and strengthening webs or

plates c c upon their outer faces, and on Fig.

1 it will be seen that these webs are flush with the upper faces of the bars and the ends of the legs.

c' c' are holes in these webs to receive the 75 bolts or rivets.

E are the pintles, each provided at one end with a flat head, the opposite end being forked or split, thus forming tangs, which, after the chain is put together, are riveted over against the outer faces of the legs A A, as indicated at e e. By preference the pintles are turned round, so that when this riveting is effected the tangs shall overlap the longer diameters of the pintle-seats a a, whereby the pintles are firmly locked in their seats, so as to be incapable of rotation relatively to the legs A A. This form of articulation is very desirable, because it insures that the wear shall come principally, 80 if not wholly, upon the circular seats in the sleeves and the adjacent portions of the pintles, thus insuring great durability of these parts.

F F are anti-friction rollers mounted upon the sleeves D D.

It will be readily seen that by the use of my invention anti-friction rollers of large diameter can be used without their projecting above the upper or outer faces of the side bars.

G G represent the deck or flooring of the 90 100

conveyer, which is made in sections of suitable length and secured to the chain by bolts passing through the deck and the holes $c'c'$ in the webs or strengthening-plates $c\ c'$.

- 5 By thus constructing the links of side bars with downward-projecting legs at their ends to receive the pintles I am enabled to construct a chain which, when straightened out in working position, has a practically-continuous surface to receive and support the platform or deck, which is very desirable under many circumstances, especially when it is requisite to form the deck or flooring of light thin material, either wood, metal, straw-board, or other analogous material for the transportation of weighty substances.

By the use of my invention I am enabled to use anti-friction rollers of quite large diameter with but slight additional weight of metal in the chains, it being apparent that the only

increase in metal which is required with an increase in diameter of the rollers is enough to increase the length of the lugs one-half of the increase of the diameter of said rollers.

What I claim is—

25

The herein-described chain for conveyers, having the separable side bars provided at their ends with downwardly-projecting lugs, the upper edges of the side bars being substantially straight from end to end, in combination with 30 anti-friction rollers between the lugs of the side bars, and the conveyer sections mounted upon the upper edges of the side bars, substantially as set forth.

In testimony whereof I affix my signature in 35 presence of two witnesses.

BENJAMIN A. LEGG.
